APPARATUS FOR DRYING FINE GRANULAR MATERIALS

Gustave Andre Vissac, Calgary, Alberta, Canada

Application July 17, 1939, Serial No. 284,977

7 Claims. (CL 34—164)

This invention relates to apparatus for drying fine granular materials.

There are a number of devices for drying wet granular materials as they pass over shaking screens by directing a current of hot air or gases downwardly through the granular materials on the screens. These devices are very effective for comparatively large or coarse materials since they not only remove the moisture by the hot air or gases but they have the advantage of forcing free water mechanically downwardly through the screens. These devices have, however, not proven very successful for extremely fine granular materials. It has been found that the openings in the screens should be at least one-half millimeter in diameter in order to allow a sufficient volume of hot air or gases to be circulated through the devices. This results in an extremely large percentage of the materials being forced downwardly through the screens by the current of air or gases.

Numerous attempts have been made to handle fine granular materials by using apparatus in which the hot gases are directed upwardly through the materials on the shaking screens. In order to be able to handle large quantities of materials in a reasonably efficient manner, it has been necessary to employ large volumes of hot gases at relatively high pressures and velocities. This results in the fine materials being raised and maintained above the screens. Consequently, the floating materials do not contact the shaking screens and, therefore, no forward movement is imparted to them. Actually, they remain more or less motionless above the screens and do not progress towards the discharge ends thereof.

It is an object of the present invention to provide a novel apparatus for drying fine granular materials, including coal, so as to avoid the disadvantages and failures of the previously used apparatus.

Another object is the provision of apparatus in which fine granular materials are periodically suspended above shaking screens by upward currents of hot gases or air for drying, and alternately are permitted to rest upon the screens, during which time they are moved towards the discharge end thereof.

A further object is the provision of apparatus for drying fine granular materials in which the hottest gases or air are directed to the wettest materials while cooler gases are directed to the drier materials.

A further object is the provision of apparatus for drying fine granular materials in which the circulation of gases or air therethrough is arranged to prevent any leakage out of the apparatus.

A still further object is the provision of apparatus of the character described in which a pul-

sating current of hot gases or air is directed upwardly through shaking screens with the pulsations synchronized with the movement of the screens.

With these and other objects in view, the invention will be apparent upon consideration of the following specification in conjunction with the accompanying drawings, in which

Figure 1 is a side elevation of the apparatus for drying the material,

Figure 2 is a transverse section through the apparatus taken substantially on the line 2—2 of Figure 1,

Figure 3 is an enlarged detail, partly in section, of a flexible coupling used between moving and stationary parts,

Figure 4 is a fragmentary horizontal sectional view taken through the outer end of the chambers of the apparatus, and

Figure 5 is an enlarged detail of a counterbalanced flap at the end of a screen.

Referring more particularly to the drawings, 10 and 11 indicate two inclined shaker screens supported by suitable oscillatable hangers 12 and 13, respectively, on each side thereof, suspended from beams 14 secured to vertical supports 15. The screens are preferably covered with wire mesh, perforated plates or wedge wire screen surfaces of proper mesh, and are oscillated in any suitable manner, such as by means of eccentrics 16 which are connected to the screens by connecting rods 17 disposed preferably at an 180° angle, so that when the eccentrics 16 are operated through any suitable source, such as a motor 18, the screens are subjected to opposed and continuous operation.

The wet granular material is delivered from a chute 20 on to screen 10 which is divided into two sections 21 and 22 extending longitudinally thereof. The material, after passing over screen 10, is transferred to screen 11 and this latter screen is likewise divided into two sections 23 and 24 extending longitudinally thereof. A pair of hoppers 25 is suspended from the screen 10 underlying approximately one half said screen and another pair of hoppers 26 is suspended from the screen and underlie approximately the other half thereof. One set of hoppers 25 and 26 is disposed beneath the section 21 of the screen 10 while the other set of said hoppers is disposed beneath the section 22 of the screen. Each of said hoppers is provided with a short pipe 27 at the opening in the bottom thereof. Similarly, a pair of hoppers 28 is suspended from the screen 11 underlying substantially one half said screen and another pair of hoppers 30 is suspended from the screen and underlie substantially the other half thereof, with one set of hoppers 28 and 30 disposed beneath the section 23 of said screen and the other set of hoppers disposed beneath the

section 24 of the screen. Each of the hoppers 28 and 30 is provided with a short pipe 21 at the opening in the bottom thereof. The hoppers under the screens 10 and 11 are arranged in the same manner.

In Figure 1, only one of each of the hoppers 25, 26, 28 and 30 is shown. Figure 2 shows the position of the pair of hoppers 25 in relation to the screen 10, the remaining hoppers being similarly disposed in relation to their respective screens.

A hood 32 is mounted on and overlies substantially the whole of the screen 10 and a hood 33 is mounted on and overlies the screen 11 in a similar manner. The hoods 32 and 33 are provided with outlet openings 34 and 35, respectively, in the ends thereof, the ends in question being the ends facing the lower ends of the shaker screens. Counterbalanced flaps 36 are mounted at each end of the hoods 32 and 33. Each flap 36 is pivotally suspended from its hood and is provided with a weighted counter-balancing arm 37 and at its lower or trailing edge with a strip 38 formed of canvas or other suitable material, see Figure 5. The trailing edges of these flaps rest upon the granular materials as they pass thereunder and said materials, now dried, are discharged from the screen 11 on to a discharge chute 40.

A pair of chambers 41 and 42 are situated side by side beneath the hoppers 25, 26, 28 and 30, both chambers communicating at their forward ends with a pair of vertically disposed pulsators 43 and 44. The pulsator 43 is divided into sections 45 and 46 while the pulsator 44 is divided into sections 47 and 48, the sections 45 and 47 communicating with the chamber 41 and the sections 46 and 48 communicating with the chamber 42. Blades 50 and 51, disposed at an angle of 90° with respect to each other, are rotatably mounted in the sections 45 and 46 of the pulsator 43, and blades 52 and 53, disposed at right angles to each other, are rotatably mounted in the sections 47 and 48 of the pulsator 44, all said blades being rotated by a suitable source of power, such as a variable speed motor 49, see Figure 2.

The pulsator 43 is connected by a pipe 54 to the flue 55 of a furnace 56 which is provided with an automatically controlled blower 57, the flue 55 being provided with a damper 58 above the pipe 54. The pulsator 44 is connected by a pipe 60 to an auxiliary air fan 61, said fan being operated by a suitable source of power (not shown) which may, if desired, be the same as that operating the pulsators. An adjustable baffle plate 62 is mounted between the pulsators 43 and 44 and it may be swung upwardly to direct hot gases from the pipe 54 to the pulsator 44 or it may be swung downwardly to direct cool air from the pipe 60 to the pulsator 43.

The chambers 41 and 42 have a plurality of outlet openings 64 formed in the tops thereof, one for each hopper disposed beneath the screens 10 and 11, and a sleeve 65 extending upwardly from each opening. From the description so far, it will be seen that the hoppers oscillate with the screens while the chambers are stationary so that it is necessary to provide a flexible coupling therebetween.

Figure 3 is an enlarged detail of the coupling between the pipe 21 of the hopper 26 and the adjacent sleeve 65 of the chamber 41. As all these couplings are the same, only one need be described in detail. Referring particularly to Figure 3, the upper end of the sleeve 65 is sloped so that it lies at a tangent to an imaginary circle drawn with its centre coinciding with the upper

5 pivot point of the hanger 12 (Figure 1) immediately thereabove. A flange 66 is formed around and extends outwardly from the upper end of the sleeve 65, said flange lying in the same plane as said sloped upper end. A plate 67 is slidably mounted on a bearing plate 68 which, in turn, is secured to the flange 66. The plate 67 has an opening 70 therein and a sleeve 71 extending upwardly from said opening and slidably fitting into the pipe 21 of the hopper 26. As a result of this construction, the sliding plate 67 lies at a tangent to an imaginary circle with its centre coinciding with the upper pivoting point of the hanger 12 above mentioned. This plate is free to slide on the bearing plate 68 between the latter and rollers 12 held thereabove by supports 13 which are mounted on the flange 66 and extend upwardly past the bearing plate 68. When the hopper oscillates with the screen 10, both a vertical and a lateral motion is imparted thereto so that the lower end of the pipe 21 moves through an arc, the centre of which is the upper pivot point of the hanger 12 referred to above. The sliding plate 67 allows the pipe 21 to move laterally while the sleeve 71 permits said pipe to move vertically. The sliding plate 67 and its sleeve 71 act as a flexible coupling to prevent gases from passing from the sleeve 65 into the atmosphere outside the device.

30 Each outlet opening 64 is provided with an adjustable damper 74 by means of which the amount of gases passing through each sleeve 65 may be regulated. Furthermore, the dampers may be pivoted downwardly or upwardly selectively to direct gases through the sleeves 65 from the bottom and/or from the top of the chambers 41 and 42.

35 The outlet openings 34 and 35 of the hoods 32 and 33 are connected to horizontal pipes 75 and 76, respectively, by means of flexible couplings similar to those just described. In this case, the bearing plates 68 are mounted directly on the ends of the hoods and the sleeves 71 of the plates 67 slidably fit into their respective horizontal pipes. These couplings function in the same manner as the previous couplings, the only difference being that the hoods oscillate while the pipes 75 and 76 remain stationary. The horizontal pipes 75 and 76 are connected at their free ends to a dust collector 77 which is connected by a suction pipe 78 to an exhaust fan 79 having a discharge pipe 80. If desired, the rearward ends of the chambers 41 and 42 may be connected to the dust collector 77 by pipes 81, each controlled by a damper 82.

40 The granular material to be treated, say, for example, fine coal, passes through the chute 20 on to the shaker screen 10. The inclined shaker screens 10 and 11 are subjected to opposed and continuous oscillation, during which time the coal passes over the screen 10 and on to the screen 11, whence it is discharged into the discharge chute 40. During its travel over these screens, the coal is constantly subjected to substantially alternate vertical and horizontal movement. The horizontal movement causes the coal to move towards the discharge ends of the screens and the vertical movement continually loosens up the coal to permit hot gases to pass freely therethrough for drying purposes. In this apparatus, the coal is subjected to intense heat as it starts to move across the screen 10 when it is wettest and then heat to which it is subjected is lessened as the coal progresses across the 45 screens and becomes dryer.

In operation, the blower 57 forces hot gases from the furnace 56 through the flue 55, the pipe 54 and the pulsator 43, into the chambers 41 and 42. At the same time, the auxiliary fan 61 forces cold air through the pipe 60 and the pulsator 44 into the chambers 41 and 42. If the gases are too hot, the baffle plate 62 may be adjusted to permit cold air from the pipe 60 to mix with the gases before the latter reach the pulsator 43 and if the air is too cold, said baffle plate may be 10 adjusted to permit hot gases from the pipe 54 to mix with the cold air before it reaches the pulsator 44. With this arrangement of the hot gas pipe 54 above the cold air pipe 60, the hot gases enter the chambers on top of the cold air and 15 as this is the natural position of these elements, they will not mix very rapidly so that the degree of mixture is mainly controlled by the baffle plate 62.

Both pulsators are driven by the motor 49 and 20 are formed with two sections with the blades of one section at right angles to the blades of the other sections. It will be noted that the sections 45 and 47 of the pulsators are open at the same time and the sections 46 and 48 are also open 25 at the same time but alternately to the opening of the former sections. In this way, charges of hot gases and cold air are admitted alternately to the chambers 41 and 42.

The mixture of hot gases and cold air is directed 30 through the outlet openings 64, the hoppers, the coal on the screens, the pipes 75 and 76, and into the dust collector 77 where any water or solid materials carried by the mixture are deposited, the gases and air being discharged by 35 the fan 79 through the pipe 80. By supplying the hot gases to the tops of the chambers 41 and 42, practically the only thing passing through the hoppers 25 is hot gases while the amount of 40 cold air in the hot gases passing through the hoppers 26, 28 and 30 progressively increases. The adjustable dampers 74 may be employed to assist in regulating the mixture passing through 45 each pair of hoppers. The more a damper is opened, the more cold air is directed into its 50 hopper as the damper more or less reaches down and scoops up cold air from the bottoms of the chambers. The drawings show each succeeding damper 74 opened to a greater extent than the previous one, beginning at the entrance end of the chambers.

As previously described, the screen 10 is divided longitudinally into two sections 21 and 22 while the screen 11 is also divided into two longitudinal sections 23 and 24. The sections 21 and 23 of these screens communicate through the hoppers 25, 26, 28 and 30 therebeneath with the chamber 41 and the sections 22 and 24 communicate through hoppers 25, 26, 28 and 30 therebeneath with the chamber 42. With this arrangement, direct connection is alternately established and disestablished between the auxiliary fan and the blower and the hoppers beneath each side of the screens so that the hot gases are directed through the bed of coal on one side only of the screens 10 and 11 at any one particular time. By alternately interrupting the flow of gases through the bed of coal on each side of the screens in this manner, the coal is alternately loosened up on each side of the screens by the oscillation thereof. 70 A steady flow of gases upwardly through the coal would tend to maintain the latter in suspension above the screens so that it would not be moved towards the discharge ends thereof.

The chamber 41 and 42 may be cleaned out 75

without appreciably interfering with the operation of the apparatus, merely by opening the dampers 82. This short circuits the gases and without the resistance of the materials on the screens, the gases quickly blow any material that may have accumulated in the chambers, into the dust collector.

The speed of reciprocation of the screens is governed by the conditions in accordance with the well known theory of shaking screens or conveyors, for example, between 250 and 300 strokes per minute. It is well known that the forward motion of the material is obtained by momentum and at the start of the return stroke of the screen. In view of this, the pulsators are operated to permit the coal to rest upon the screens during the forward movement thereof and to permit the hot gases to raise the coal above the screens during their return movement. As the hot gases are directed upwardly through the screens, they raise and suspend the coal thereabove. This loosens up the coal and circulates hot gases therethrough, thus constituting a drying period. When the coal on one side of a screen is being dried in suspension, the coal on the other side of the screen is resting thereon and is being moved forwardly, thus constituting a period of movement towards the discharge end of the screen.

The coal is subjected to the greatest heat as it passes over the hoppers 25 where it is wettest and as it progressively passes over the hoppers 26, 28 and 30 it is subjected to increasingly less heat as it becomes dryer. Too much heat applied to dried fine coal is injurious to the coal and it is very liable to create an explosive mixture at the discharge end of the apparatus.

The speed of operation of the pulsators may be varied to obtain the best results with the material being dried. These pulsators create a series of pulsations which are subject to the well known laws of air and sound vibration. The amplitude of the pulsations, for a given amount of energy, may be greatly increased by obtaining the proper periods of pulsation in accordance with the intensity of the flow of gases and the size and volume of the chambers 41 and 42, or, in other words, by creating a condition of resonance in the apparatus. By employing a variable drive for the pulsators, the timing of the pulsations may be varied to suit the varying conditions. The type, condition and density of the material being dried effects these conditions. In this way, the gases in the apparatus constantly pulsate in resonance with the apparatus, thus maintaining it at its maximum efficiency with a minimum of power.

The combined capacity of the blower 57 and the auxiliary fan 61 is just sufficient to overcome the resistance of the pipes and joints below the screens and that of the bed of coal on the screens, thus leaving a very low pressure above the bed. The capacity of the exhaust fan 79 is sufficient to overcome the resistance of the dust collector 77 and the pipes and joints above the screens and it is slightly higher than the combined capacity of the blower and the auxiliary fan. The depression in the apparatus is slightly below the atmospheric pressure in the room in which the apparatus is located, so that there is very little leakage at the joints between the stationary and moving parts of the apparatus, and if any leakage does exist, air is drawn into the apparatus rather than hot gases being expelled therefrom.

It is to be understood that the term "hot gases" as used in the foregoing description and in the following claims, includes hot air. For example, air may be heated in the furnace and used in drying the granular materials.

Various modifications may be made in this invention without departing from the spirit thereof or the scope of the claims, and therefore the exact forms shown are to be taken as illustrative only and not in a limiting sense, and it is desired that only such limitations shall be placed thereon as are set forth in the accompanying claims.

What I claim as my invention is:

1. Apparatus for drying fine granular material, comprising a screen for receiving and agitating the material, means for shaking the screen in a longitudinal direction, means for directing a flow of hot gases upwardly through the material to raise the latter above the screen, means for making the gases directed through the screen adjacent its discharge end cooler than those directed therethrough at its forward end, and means for periodically interrupting the flow of gases during movement of the screen towards its discharge end to permit the material to rest thereon during each interruption, whereby the material is subjected to periods of drying and to periods of movement towards the discharge end of the screen.

2. Apparatus for drying fine granular material, comprising a screen for receiving and agitating the material, means for shaking the screen in a longitudinal direction, a hopper disposed below said screen, a hood disposed above the screen in an area overlying the hopper, means for directing a flow of hot gases through the hopper and through the material to raise the latter above the screen, means for withdrawing the gases from the hood, and means for periodically interrupting the flow of gases during movement of the screen towards its discharge end to permit the material to rest thereon during each interruption, whereby the material is subjected to periods of drying and to periods of movement towards the discharge end of the screen.

3. Apparatus for drying fine granular material, comprising a screen for receiving and agitating the material, means for shaking the screen in a longitudinal direction, a hopper disposed below said screen, a hood disposed above the screen in an area overlying the hopper, a blower adapted to direct hot gases through the hopper and through the material to raise the latter above the screen, an exhaust fan connected to the hood for withdrawing the gases therefrom, the capacity of the exhaust fan being at least slightly greater than that of the blower, and means for periodically interrupting the flow of gases during movement of the screen towards its discharge end to permit the material to rest thereon during each interruption, whereby the material is subjected to periods of drying and to periods of movement towards the discharge end of the screen.

4. Apparatus for drying fine granular material, comprising a screen for receiving and agitating the material, means for shaking the screen in a longitudinal direction, a pair of hoppers disposed below the screen, a hood disposed above the screen in an area overlying the hoppers, means for directing a flow of hot gases through the hoppers and through the material to raise the latter above the screen, means for withdrawing the gases from the hood, and means for alternately interrupting the flow of gases to each hopper

during movement of the screen towards its discharge end to permit the material thereabove to rest on the screen during each interruption, whereby the material is alternately subjected to periods of drying and to periods of movement towards the discharge end of the screen.

5. Apparatus for drying fine granular material, comprising a screen for receiving and agitating the material, means for shaking the screen in a longitudinal direction, a hopper disposed below the screen, a hood disposed above the screen in an area overlying the hopper, a chamber communicating with the interior of the hopper, means for directing a flow of hot gases through the chamber and through the material to raise the latter above the screen, means for selectively mixing cold air with the gases before passing through the screen, and means for periodically interrupting the flow of gases during movement of the screen towards its discharge end to permit the material to rest thereon during each interruption, whereby the material is subjected to periods of drying and to periods of movement towards the discharge end of the screen.

6. Apparatus for drying fine granular material, comprising a screen for receiving and agitating the material, means for shaking the screen in a longitudinal direction, a plurality of hoppers disposed longitudinally of the apparatus below the screen, a hood disposed above the screen in an area overlying the hoppers, a chamber communicating with the interiors of the hoppers, means for directing a flow of hot gases through the top portion of the chamber and through the material to raise the latter above the screen, means for supplying a flow of cold air to the chamber beneath the hot gases, means for directing some cold air along with the hot gases through at least one hopper adjacent the discharge end of the screen, and means for periodically and simultaneously interrupting the flow of gases and cold air during movement of the screen towards its discharge end to permit the material to rest on the screen during each interruption, whereby the material is subjected to periods of drying and to periods of movement towards the discharge end of the screen.

7. Apparatus for drying fine granular material, comprising a plurality of screens for receiving and agitating the material, means for shaking the screen in a longitudinal direction, a plurality of hoppers disposed below the screens, a hood disposed above each screen in an area overlying the hoppers thereunder, a chamber communicating with the interiors of the hoppers, means for directing a flow of hot gases through the top portion of the chamber and through the material to raise the latter above the screens, means for supplying cold air to the chamber beneath the hot gases, means for selectively intermixing at least a little of the hot gases and cold air before entering the chamber, means for directing some cold air along with the hot gases through at least some hoppers, means for controlling the amount of cold air directed through each hopper, means for withdrawing the mixture of gases and cold air from the hoods, and means for periodically and simultaneously interrupting the flow of gases and cold air during movement of the screens towards their discharge ends to permit the material to rest on the screens during each interruption, whereby the material is subjected to periods of drying and to periods of movement towards the discharge end of the screen.
